DESIGN FOR A CABINET FOR A BEVERAGE COOLER

Duffy A. Matot, Wilmette, Ill.

Application June 26, 1939, Serial No. 85,697

Term of patent 14 years

To all whom it may concern:

Be it known that I, Duffy A. Matot, a citizen of the United States of America and a resident of Wilmette, Cook County, Illinois, have invented a new, original, and ornamental Design for a Cabinet for a Beverage Cooler, of which the following is a specification, reference being had to the accompanying drawing, forming a part hereof.

The figure of the drawing is a perspective view of a cabinet for a beverage cooler, showing my new design, the left hand end of the cabinet as

viewed in the drawing being identical with the right hand end shown, and the rear wall of the cabinet constituting a plane vertical surface having a toe board and a top edge substantially as viewed from the end.

I claim:

The ornamental design for a cabinet for a beverage cooler, substantially as shown and described.

DUFFY A. MATOT.
